UNITED STATES PATENT OFFICE.

ABBOT AUGUSTUS LOW, OF HORSESHOE, NEW YORK.

ANDIRON FOR FIREPLACES.

SPECIFICATION forming part of Letters Patent No. 746,539, dated December 8, 1903.

Application filed December 2, 1902. Serial No. 133,540. (No model.)

To all whom it may concern:

Be it known that I, ABBOT AUGUSTUS LOW, a citizen of the United States, residing at Horseshoe, St. Lawrence county, and State of New York, have invented certain new and useful Improvements in Andirons for Fireplaces, of which the following is a specification sufficient to enable others skilled in the art to which the invention appertains to make 5 and use the same.

My present invention is an improvement upon the structure shown and described in my concurrent application, Serial No. 129,358, filed October 31, 1902, in which the andirons 15 are united by lateral members and support a fuel basket or grate between them.

The improvement is designed to provide for the convenient heating or cooking of substances between the andirons; and the invention consists, essentially, in an adjustable and removable shelf or gridiron supported upon a series of projections or shoulders on the inner sides of the andiron-standards, as hereinafter described, and claimed specifically.

In the accompanying drawings, Figure 1 is a front elevation of my improved andiron; Fig. 2, a top view of the same, and Fig. 3 an end elevation thereof. Fig. 4 is a front elevation with the gridiron removed; Fig. 5, a top view showing the T-bar in place, and Fig. 6 a sectional elevation upon plane of line 6 6, Fig. 5.

A A' represent the andirons, united by the 35 transverse members or rods a a.

B is the open-work fuel-basket, formed with the flanges b b, which rest in the ways a⁵ a³, formed on the inner sides of the andiron-uprights. The functions of this suspended grate 40 or fuel-basket B are fully set forth in my concurrent application hereinbefore referred to.

a⁴ a⁴ are lugs or shoulders formed upon the inner sides of the andiron-uprights to afford a series of horizontal supports for the removable gridiron or shelf C, which is preferably formed with a series of slots or openings c c to expose articles placed upon the gridiron or shelf C more directly to the heat of the incandescent fuel below. Any desired 45 number of these removable gridirons or shelves may be provided, as may be found most expedient in adapting the device to various uses, and their adjustment with relation to the grate B and to each other is amply

provided for by the series of shoulders a⁴ a⁴, 55 arranged at different heights.

D D are extension-brackets made adjustable upon the front standards of the andirons by any suitable means, as by forming the brackets with longitudinal slots d d, 60 through which pass set-screws d' d', as shown in the drawings, or by any other mechanical expedient.

Each extension-bracket D is formed at its upper end with a loop or hook d² d² for the 65 reception of the ends e e of a T-bar E, the middle member e' of which fits in a semicircular notch or depression f in one of the rear cross-bars, several of which latter may be provided. By this means when the gridiron 70 C is not in actual use the extension-brackets may be raised to the proper level and the T-bar E put in position, so that its middle member e may be utilized as an arm or crane upon which to hang a pot, kettle, or other utensil 75 above the fire-basket B.

What I claim as my invention, and desire to secure by Letters Patent, is—

1. The combination with andirons united by transverse members and having lugs upon 80 their adjacent faces, of brackets adjustable on the front standards of the andirons, and a removable support mounted on said standards and one of the said transverse members.

2. The combination of andirons united by 85 transverse members between the rear standards, extension-brackets adjustable upon the front standards, and a T-shaped cross-bar engaging the said extension-brackets in front and one of the transverse members at the 90 rear for the purpose and substantially in the manner described.

3. The combination of andirons united by transverse members between the rear standards, said transverse members being formed 95 with semicircular depressions midway of their length, extension-brackets adjustable upon the front standards and formed with loops or hooks at their upper ends, and a T-shaped cross-bar engaging the hooks or loops on the extension-brackets and the semicircular depressions in the transverse rear members, for 100 the purpose and substantially in the manner described.

ABBOT AUGUSTUS LOW.
